Inventor

John E. Beach

United States Patent Office.

EDGAR B. BEACH, OF WEST MERIDEN, CONNECTICUT.

Letters Patent No. 63,690, dated April 9, 1867.

IMPROVEMENT IN CONVERTIBLE RIFLE SIGHTS.

The Schedule referred to in these Letters Patent and making part of the same.

TO ALL WHOM IT MAY CONCERN:

Be it known that I, EDGAR B. BEACH, of West Meriden, in the county of New Haven, and State of Connecticut, have invented a new Improvement in Rifle Sight, and I do hereby declare the following, when taken in connection with the accompanying drawings and the letters of reference marked thereon, to be a full, clear, and exact description of the same, and which said drawings constitute part of this specification, and represent, in—

Figure 1, a top view, showing the sight as open.

Figure 2, a side view of the same.

Figure 3, a top view, showing the same sight turned up as a covered sight; and in

Figure 4, a side view of the same.

This invention relates to an improvement in sights for rifles, whereby the sight may be changed at pleasure from open to covered, or *vice versa*; without removing the sight from the barrel, and consists in the combination of an open and covered sight arranged so that either one or the other may be used at pleasure. Heretofore sights have been made either open or covered, and when it is desired to change the sight from one to the other, it is necessary to remove the one before the other can be attached. This causes the trouble of adjustment at every change, and necessitates several shots to make the adjustment. By my invention this difficulty is entirely overcome; and to enable others skilled in the art to construct and use my improvement, I will proceed to describe the same, as illustrated in the accompanying drawings.

A is the barrel of an ordinary rifle, B the slide, to which the sight is fixed, and is attached to the barrel by a transverse dove-tail groove in the usual manner, so as to be adjusted to the right or left. Near the centre of the said slide is formed a spring hinge, a, to which the open sight d and the covered sight c are fixed, so that the covered sight being down, as in figs. 1 and 2, the open sight is up, and is held in that position by a spring beneath, or any equivalent therefor. If at any time the sportsman desires to change from the open to the covered sight, as seen in figs. 3 and 4, (the hinge permitting him so to do,) in which movement the open sight is turned down, and the sights stand in the position as seen in figs. 3 and 4; the bead is fixed within the cover in the usual manner, and so as to correspond precisely with the open sight, so that the adjustment of one is the adjustment of both, and the change from one to the other in no way affects the adjustment; thus the sportsman has upon his arm at pleasure either a covered or open sight.

Having, therefore, thus fully described my invention, what I claim as new and useful, and desire to secure by Letters Patent, is—

The combination of the covered sight c, and open sight d, constructed and arranged so as to be changed to present either the one or the other, substantially in the manner described.

EDGAR B. BEACH.
